UNITED STATES PATENT OFFICE

JOHN NEALE, OF LONDON, AND HORACE ROBERT WATSON, OF WIMBLEDON, ENGLAND

CONTROL OF RAILWAY AND LIKE VEHICLES

Application filed November 9, 1929, Serial No. 406,022, and in Great Britain November 9, 1928.

This invention has reference to improvements relating to the control of railway and like vehicles where relative movement takes place between a light sensitive cell 5 permanently illuminated by a local source of current and an interrupter blade to cut off the light from the cell. It will of course be understood that the invention is applicable to any other mechanism wherein 10 an illuminated cell is darkened by an interrupter blade.

According to the present invention the action of the interrupter blade in cutting off the local light from the light sensitive 15 cell is neutralized when desired by an additional source or sources of light and thus the light sensitive cell remains illuminated when desired in spite of the presence of the interrupter blade. It follows, therefore, 20 that control, signal or other mechanism in connection with the light sensitive cell will not be affected when the additional lights are active.

This neutralization of the effect of the 25 interrupter blade may be obtained in various ways, by direct or reflected illumination of the light sensitive cell. Thus we have the choice of two alternative operative effects on the passing of the interrupter, 30 according to whether the additional lights are lighted or not, and thus control is effected without mechanical movement of the blade. The preferred use of the illuminated condition of the cell being to withhold 35 train brakes, it will be seen that accidental failure of the interrupter lamps would result in the application of the brakes and never in a false security.

The invention will now be described by 40 way of example only with reference to the accompanying drawings, in which:—

Fig. 1 shows an illuminated cell unit about to be obscured by an interrupter blade 45 with neutralizing lamps, which it is approaching.

Figs. 2 and 3 show alternative arrangements of neutralizing lamps.

Fig. 4 shows a further alternative arrangement.

Fig. 5 represents an elevation corresponding to Fig. 4.

Referring now to Fig. 1, A represents the lamp used for normal illumination of the light sensitive cell B, A and B both being 55 suitably shielded from exterior illumination, such as daylight. C represents the interrupter blade. D represents one of a series of neutralizing lamps.

As applied in one form to a railway signalling and controlling system, A and B form an illuminated light sensitive unit which has movement relative to the stationary blade C and lamps D. Thus the action will be that if the interrupter blade C passes 60 between A and B and the lamps D are not illuminated, the light will be cut off from B and any mechanism in connection with it will be operated, such as brakes and/or signals. If, however, the lamps D are illuminated 65 when C passes between A and B, light passing from A to B will be cut off, but will be replaced by the light from the lamps D. Therefore any mechanism adapted 70 to be operated by the darkening of the 75 light sensitive cell will not function.

In Fig. 2 the lamps D are shown placed on either side of the blade C, thus allowing the mechanism to continue to function if the direction of travel of the vehicle, upon 80 which the illuminated light sensitive unit is mounted, is reversed.

Fig. 3 shows a further construction, wherein the lamps D are mounted centrally below the blade. Light given off from the 85 lamps D and operating the cell B may be either reflected or direct.

Figs. 4 and 5 show a further constructional form characterized by the fact that the lamps D are optically arranged to cast 90 a beam towards the oncoming vehicle and approximately parallel to its direct travel. For this purpose the cell B has apertures both towards the lamp A and the lamps D.

We claim:—

1. A control of the character set forth comprising a light-sensitive cell, a source of light constantly illuminating said cell, an interrupter blade, and an additional source of illumination associated with said 95

- interrupter blade, the arrangement being such that on relative movement between the said light-sensitive cell with its source of illumination and the interrupter with its associated source of illumination the said cell is illuminated by the additional source of light on the passage of the interrupter blade between said light-sensitive cell and its source of illumination, when said additional source of illumination is functioning.
10. 2. A control according to claim 1 wherein the additional source of illumination comprises a plurality of lamps located to one side of said interrupter blade.
15. 3. A control according to claim 1 wherein said source of illumination comprises an electric lamp located to one side of said interrupter blade.
20. 4. A control of the character specified comprising a light-sensitive cell and a source of illumination mounted in spaced relation on a moving object, a stationary interrupter blade, said blade being so positioned that on the passage of the moving object said blade interrupts the passage of light from said source of illumination to said light-sensitive cell, and an additional source of illumination being so disposed relatively to said interrupter blade that during
25. 30. the passage of said object said additional source of illumination, when functioning, illuminating the light-sensitive cell.
35. 5. A control for the purpose specified comprising a light-sensitive cell, a source of illumination normally illuminating said cell, a stationary interrupter blade, said blade being so located that on the passage of said cell with its source of illumination said blade obstructs the illumination of said cell and additional sources of illumination associated with said blade and located in the direction of movement of said cell.
40. 6. A control for the purpose specified comprising a selenium cell, an electric lamp normally illuminating said cell, said cell and lamp being arranged in spaced relation on an object to be controlled, a stationary interrupter blade, said blade being so arranged that on the passage of said object it
45. 50. 55. passes between said cell and said lamp, and a plurality of additional electric lamps arranged in a row parallel to said blade, said cell having apertures directed both towards the first mentioned lamp and towards the additional lamps.

In testimony whereof, we have signed our names to this specification at London, England, 17th day of October, 1929.

JOHN NEALE.

60. HORACE ROBERT WATSON.
